J. F. LOCKWOOD.

SLIPPER CASE.

No 18,677.

Patented Oct. 9, 1886

UNITED STATES PATENT OFFICE.

JAMES F. LOCKWOOD, OF PHILADELPHIA, PENNSYLVANIA.

DESIGN FOR A SLIPPER-CASE.

SPECIFICATION forming part of Design No. 18,677, dated October 9, 1888.

Application filed August 3, 1888. Serial No. 281,888. Term of patent 14 years.

To all whom it may concern:

Be it known that I, JAMES F. LOCKWOOD, a citizen of the United States, and a resident of Philadelphia, Pennsylvania, have invented 5 a new and original Design for a Slipper-Case, of which the following is a specification.

My design for a slipper-case is fully shown in the accompanying drawing.

The leading feature of the design is the 10 circular plaque, having the opposite tablets corresponding in outline to the heel and sole of a slipper, the sole portion of each tablet being covered by a raised shell in imitation of the upper portion of a slipper; and a diamond-shaped panel being interposed between the

heel portions of the tablets. Minor features of the design are the scale-like ornamentation of the plaque and the rope-like bead around the edge of the same.

I claim—

The design for a slipper case, substantially as described and shown.

In testimony whereof I have signed my name to this specification in the presence of two subscribing witnesses.

JAMES F. LOCKWOOD.

Witnesses:

EDWARD M. RILEY,
HARRY SMITH.
